UNITED STATES PATENT OFFICE

2,450,017

METHOD OF PRODUCING ANIMATED
CARTOONSRobert Place, Glen Cove, N. Y., assignor to Place
Process, Inc., Washington, D. C.

Application June 8, 1944, Serial No. 539,245

18 Claims. (Cl. 88—16)

1

The present application is a continuation-in-part of my copending application Serial No. 25,309, filed June 6, 1935, renewed March 25, 1939, and now Patent No. 2,351,634 issued June 20, 1944, and relates to improvements in the production of moving pictures and, more particularly, comprehends methods of producing animated cartoon pictures.

In prior methods of making animated cartoons, the artist's drawings are hand-traced with black India ink on individual sheets of transparent Celluloid, after which the ink tracings are opaqued with a layer of tone or color-producing material on the reverse side of the Celluloid sheets. Each Celluloid sheet is then superposed upon a sheet bearing a painted or other reproduction of a suitable background and the composite picture is photographed to produce a master negative. Many disadvantages characterize the foregoing practice, most pronounced of which may be mentioned the time and expense incident to hand tracing of the artist's drawings on the large number of individual Celluloid sheets necessary to produce a complete series of animated pictures and the inaccuracies resulting from hand mounting each Celluloid sheet before the camera to be photographed. Further, in the above practice, the traced and opaqued Celluloid sheets when once photographed, are ill adapted for storage for future use to employ the same action scenes on different backgrounds because of the bulk of the sheets and because the tracings and opaque coatings deteriorate and become obliterated.

Among the objects of the present invention are to overcome or greatly to reduce the foregoing and other disadvantages of heretofore known methods and in this connection, to devise a novel method whereby better animated pictures may be produced more quickly and at less cost.

A feature of the invention comprises photographically reproducing the artist's drawings upon Celluloid or other transparent medium with the accompanying advantage of eliminating the slow and inaccurate hand tracing step. As a further advantage of this feature, any tone or color in line can be consistently produced by varying the exposure or by bleaching and dying the film, whereas black lines only can consistently be obtained by the tracing method because of the necessary use of black India ink. Such transparent bodies upon which the animated drawings have been photographically reproduced have the further object and advantage over ink-traced Celluloids in that they may be stored over long periods of time

without deterioration and re-used whenever a similar action is wanted in a future film.

As a further feature of the invention, the drawings may be photographically reproduced on the sensitized transparent body in such a manner that upon development thereof a variation in elevation exists between the image lines and the surface of the transparency. Such variation in elevation has the important advantage, particularly when an opaque coating is applied to the image carrying side of the body, of providing a border to guide the opaquer's brush and confine the coating material to the area within the outlines of the images.

Another feature of the invention, and one of major importance, resides in photographically reproducing the drawings to be animated in series upon successive frames of a strip or roll of Celluloid or other transparent medium and thus to dispense with the prior practice of providing an individual Celluloid sheet for each one of the drawings of the series. Objects and advantages of providing such a step, in addition to the reduction in labor and cost of materials, are numerous and include the following; the necessary application of toning or shading material or opaquing of the figures on the strip is facilitated in that the strip may be merely unreeled before the worker instead of involving the separate handling of a large number of individual sheets; whereas a traced drawing is of the same size as the artist's drawing, the photographic reproduction on the strip of the artist's drawing in my invention can be reduced to any desired size for more convenient opaquing with resultant saving in time and material; whereas in prior practice the background must be of a size to correspond with the traced figures comprising the foreground superposed thereon, the backgrounds for use with the strips of my invention need not be of corresponding size since difference in size or proportion can be compensated by merely varying the distance between the strip and background when the same are positioned before the camera reproducing the master negative; and in this manner of backgrounding, effective lighting or shading of the background can be produced without disturbing the foreground figures.

Other objects and advantages of the present invention will be apparent from the following detailed explanation thereof taken in conjunction with the accompanying drawings which are illustrative of a preferred embodiment.

In the drawings:

Fig. 1 is a perspective view illustrating preparation of the usual artist's drawings;

Fig. 2 is a diagrammatic view showing the step of photographing the artist's drawings in series on successive frames of a sensitized film;

Fig. 3 is a diagrammatic view showing another step of transferring the images on the film of Fig. 2 to successive areas of a transparent strip;

Fig. 4 is a fragmentary enlarged plan view of the transparent strip of Fig. 3;

Fig. 5 is a view similar to Fig. 4 showing the image opaqued at the rear of the image in varying tones to complete the cartoon image;

Fig. 6 is a plan view showing the completed image bearing strip of Fig. 5 superposed on a background; and

Fig. 7 is a diagrammatic view illustrating the step of photographing the series of composite pictures of Fig. 6 on successive frames of a sensitized film.

As indicated in Figure 1, the first step in the practice of the present invention includes the provision of the usual sequence or series of artist's drawings 10. However, since the drawings are to be photographed instead of traced, they may vary from the conventional type in any manner which may be found suitable. For example, they may be larger than animation scale to any extent desired by the artist and then reduced to the desired animation scale in well known manner when photographically reproduced upon the transparent medium and they may contain fine detail and artistic effects not capable of being traced in normal animation scale upon Celluloid in India ink but which are capable of being photographically reproduced as comprehended by the present invention.

The series of drawings 10 are photographed as indicated in Fig. 2 upon successive frames of any movie film or roll film 12 which may be of standard width if desired, by positioning the same consecutively before the camera and exposing the progressing film to consecutively photograph each drawing, thus to provide a very contrasty line negative when the film is developed. By using film sensitive, for example, to red, it is possible to photograph drawings done in red, while marks and notations in blue, for example, will not be photographed. This has the advantage that the animator may do his rough sketches in blue pencil and then go over them with red pencil on the lines he wants to have reproduced and it will not be necessary to erase the blue pencil marks before the drawing is photographed. Further, for example, he may make notes or write instructions on the face of the drawing in blue pencil, as none of the blue marks will be reproduced on the film.

The negative film images thus provided are then printed as indicated in Fig. 3 on successive frames or areas of a preferably larger strip of Celluloid or other transparent material 14, which has been coated with a sensitive photographic emulsion. The transparent strip 14 as well as the film 12 may have the images thereon arranged transversely of its length as shown in Figure 4 or longitudinally thereof as shown in the plan view fragments at the sides of Figure 3. Since the photographed line drawings reproduced on the strip are to be opaqued, it is preferable, particularly if a small size standard width movie film negative is used, to provide a strip having a greater width and print thereon from the negative by means of an enlarger in order that the figures may be of a more convenient size to color or opaque. The opaque coating may be applied in well known manner on the back of the strip within the area of the figures to comprise the

foreground of the completed picture and to prevent the background from showing through. The coating may be of any suitable material and if colored pictures are to be produced, appropriate colors may be used to opaque instead of solid black or white. A transparent strip having its series of images opaqued and completed is fragmentarily illustrated at 16 in Fig. 5. It is understood however that a transparent body in the form of a strip having images on successive areas thereof such as 16 represents only one form of the present invention which comprehends the use of a transparent body in any other form such as individual sheets or cells for each image or groups of images to be animated.

By varying the exposure, or by bleaching or dyeing the transparent strip, individual sheet or other body, any tone or color in line can be produced. This is useful, particularly for color films, as a sharp black outline, such as results from India tracing ink, is not as desirable as a softer grayish outline or a colored outline.

In printing upon the sensitized transparent body from the negative film, it will be apparent that the relative size of the figures can be regulated as desired by varying the distance of the strip from the negative film. In shots which show a ball or other object moving toward or away from the camera in prior processes, it was necessary to draw and trace the same object in varying sizes from the smallest size to the largest size. In my method, however, one drawing is all that is necessary, since the varying sizes may be made by adjusting the enlarging printer.

After any normal action, such as walking or running has once been animated or drawn, it need never be drawn again, as the negative film thereof can be kept on file and reproduced when the action is again wanted in any size, any position on the film and moving in either direction simply by adjusting the enlarging printer which enlarges and reproduces the negatives on the sensitized transparent strip or other body. It will thus be apparent that the total number of drawings needed to produce a complete animated picture film according to my process is considerably less than heretofore; in some cases, as low as half as many, or even less, particularly where the same characters are repeatedly used in the same or different films.

The photographed transparent roll or strip, individual sheets or cells, or other body can also be filed away for future use in a film calling for similar action. The opaque coatings, usually water colors, which would quickly dry and crack off, are preferably washed off before storing the strip. This may be easily done without affecting the photographic outlines, whereas such washing obliterates or destroys a traced outline and precludes storage for future use of traced Celluloids.

To produce the final film or master negative, the appropriately opaqued image on the transparent body as on the strip 16, is positioned in front of the desired background as shown at 18 in Fig. 6, and the composite picture is photographed. As indicated in Fig. 7, the strip may be unwound and each section or picture held in position between the camera and the background while the camera film 20 is correspondingly progressed to photograph the composite pictures in the proper order. Suitable apparatus for this purpose is available and well known in the art.

The transparent strip 16 or other image carrying body may be photographed either from the

image carrying side thereof or from the opposite side thereof, the important thing being that the opaque coating be applied to the transparency at the rear of the image in order to complete the cartoon image and that the image be photographed from the completed face thereof.

It has been impracticable heretofore to opaque an ink traced image carrying side of the cell since the ink and coating material are soluble to an extent sufficient to result in blurring or other impairment of the opaqued image. It has been customary therefore in prior methods to apply the opaque coating to the face of the cell opposed to the ink traced image carrying face.

The fact that either side of the image carrying transparent body may be opaqued according to the present invention gives rise to important advantages. Among them may be mentioned that the same action or animation sequence represented on the cells or strip areas to move in one direction may be made to move in the opposite direction simply by washing off the opaque coating as first applied and opaquing the opposite face of the cell or strip which would be at the rear of the images when the direction of motion is reversed. Perhaps the greatest advantage however arises where the artist's drawings are photographically reproduced on the sensitized individual sheets or cells, strip areas or other transparent body in such a manner that upon development thereof a variation in elevation exists between the image lines and the transparent surface. Usually such variation will take the form of elevated image lines composed of the fixed sensitizing material the remainder of which has been washed away during the development stage. Such variation in elevation although slight produces a well defined image outline and when the opaque coating material is applied to the image carrying face of such a body the image lines provide a physical in addition to a visible guide for the opaquer's brush or pen and also operate to confine the coating material within the outlines of the image.

Painted backgrounds of the conventional size heretofore used are readily adaptable for use in my process and if the proportions thereof are too large for the transparent body pictures which comprise the foreground, the body and background may be spaced apart a sufficient distance so that the composite will be photographed by the camera in proper proportions obtained by adjusting the transparent body and background relative to the camera. When the background is spaced from the foreground, the same background may be subjected to various lighting effects, for example, to give the appearance of night or day, whereas with the background in contact with the foreground pictures as heretofore, separate backgrounds must be provided to produce such effects.

The fact that the novel strip of my invention is moved before the camera taking the master negative, makes particularly adaptable to the process a novel backgrounding feature wherein photographs of painted backgrounds may be used instead of the paintings themselves whose rough surfaces would become chipped off or scratch the strip when it is passed thereover. The use of such photographs is advantageous over the use of the original painted background in addition to the smooth surface thereby provided in that as many reproductions of the artist's background may be made as desired and colored or shaded to produce a variety of back-

ground effects from the same background as originally drawn. Further, photographic reproductions of backgrounds can be readily made similar in size to the strip or in any other desired size and may be reduced from the original drawing which often is relatively large better to enable the artist to introduce detail.

It is understood that the present invention embraces modifications and deviations from the method herein described such as come within the scope of the following claims.

The terms "tones" appearing in the claims is intended to be a generic expression to include shades and colors.

15 The term "drawings" as used in the following claims is employed generically to embrace all equivalents of and substitutes for artists' drawings such as pictures of any kind including reproductions of drawings, photographs of figures, etc.

20 I claim:

1. The method of producing animated cartoons from a series of cartoon drawings which comprises, photographically producing images of 25 said series of drawings on successive areas of a transparent strip, opaquing the image bearing face of the strip within outlines of the images in varying tones to complete the cartoon images, and photographing the series of completed images 30 on successive frames of a sensitized film.

2. The method of producing animated cartoons which comprises, providing a series of cartoon drawings, photographing the series of drawings on successive frames of a sensitized film, 35 transferring the images on said film to successive areas of a transparent strip, opaquing the image bearing face of the strip within outlines of the images in varying tones to complete the cartoon images, and photographing the series of completed images 40 on successive frames of a sensitized film.

3. The method of producing animated cartoons which comprises, providing a series of cartoon drawings, photographing the series of drawings 45 in reduced size on successive frames of a sensitized film, transferring the images on said film to successive areas of a transparent strip in a relatively larger size, opaquing the image bearing face of the strip within outlines of the images in varying tones to complete the cartoon images, and photographing the series of completed images 50 on successive frames of a sensitized film.

4. The method of producing animated cartoons from a series of cartoon drawings which 55 comprises, producing colored line photographic images of said series of drawings on successive areas of a transparent strip, opaquing the image bearing face of the strip within outlines of the images in varying tones to complete the cartoon images, and photographing the series of completed images 60 on successive frames of a sensitized film.

5. The method of producing animated cartoons which comprises, providing a series of cartoon drawings, photographing the series of drawings on successive frames of a sensitized film, producing colored line photographic images of the images on said film on successive areas of a transparent strip, opaquing the image bearing 70 face of the strip within outlines of the images in varying tones to complete the cartoon images, and photographing the series of completed images on successive frames of a sensitized film.

6. The method of producing animated cartoons 75 which comprises, providing a series of cartoon

drawings, photographing the series of drawings in reduced size on successive frames of a sensitized film, producing colored line photographic images of the images on said film in relatively larger size on successive areas of a transparent strip, opaquing the image bearing face of the strip within outlines of the images in varying tones to complete the cartoon images, and photographing the series of completed images on successive frames of a sensitized film.

7. In the production of animated cartoons from a series of cartoon drawings, the method of making an image bearing strip which comprises, photographically producing images of the series of drawings on successive areas of a transparent strip, and opaquing the image bearing face of the strip within outlines of the images in varying tones to complete the cartoon images.

8. The method of producing an image bearing strip for use in the production of animated cartoons which comprises, providing a series of cartoon drawings, photographing the series of drawings on successive frames of a sensitized film, transferring the images on said film to successive areas of a transparent strip, and opaquing the image bearing face of the strip within outlines of the images in varying tones to complete the cartoon images.

9. In the production of animated cartoons from a series of cartoon drawings, the method of making an image bearing strip which comprises, producing colored line photographic images of the series of drawings on successive areas of a transparent strip, and opaquing the image bearing face of the strip within outlines of the images in varying tones to complete the cartoon images.

10. The method of producing an image bearing strip for use in the production of animated cartoons which comprises, providing a series of cartoon drawings, photographing the series of drawings on successive frames of a sensitized film, producing colored line photographic images of the images on said film on successive areas of a transparent strip, and opaquing the image bearing face of the strip within outlines of the images in varying tones to complete cartoon images.

11. The method of producing animated cartoons from a series of cartoon drawings which comprises, photographically producing images of said series of drawings on successive areas of a transparent strip, opaquing the image bearing face of the strip within outlines of the images in varying tones to complete the cartoon images, placing said strip upon a photographic reproduction of a cartoon background and sliding the strip thereacross to successively arrange the series of opaqued images on said strip in coating relation with said background and photographing the series of composite pictures on successive frames of a sensitized film.

12. The method of producing animated cartoons which comprises, providing a series of cartoon drawings, photographing the series of drawings in reduced size on successive frames of a sensitized film, transferring the images on said film to successive areas of a transparent strip in a relatively larger size, opaquing the image bearing face of the strip within outlines of the images in varying tones to complete the cartoon images, providing a cartoon background, photographically reproducing said background, placing said strip upon said photographically reproduced background and sliding the strip thereacross to successively arrange the series of opaqued images on said strip in coating relation with said photo-

graphically reproduced background, and photographing the series of composite pictures on successive frames of a sensitized film.

13. The method of producing animated cartoons from a series of cartoon drawings which comprises, photographically producing images of said series of drawings on successive areas of one face of a transparent strip in such a manner as to provide a variation in elevation between the image line and the adjacent surface of said face, opaquing the image carrying face of the strip within outlines of the images in varying tones to complete the cartoon images, and photographing the series of completed images on successive frames of a sensitized film.

14. In the production of animated cartoons from a series of cartoon drawings, the method of making an image bearing strip which comprises, providing a transparent strip having successive sensitized faces, exposing said successive sensitized faces to said series of drawings, developing the exposed faces to provide a variation in elevation between the photographically produced image line and the adjacent area of said faces, and opaquing the image carrying faces within outlines of the images in varying tones to complete the cartoon images.

15. The method of producing animated cartoons from a series of cartoon drawings which comprises, photographically producing images of said series of drawings on successive sensitized transparent surfaces in such a manner as to provide a variation in elevation between the image line and the adjacent surface, opaquing the image carrying side of said transparent surfaces within outlines of the images in varying tones to complete the cartoon images and utilizing the variation in elevation to confine the opaquing material within the outlines, and photographing the series of completed images on successive frames of the sensitized film.

16. In the production of animated cartoons from a series of cartoon drawings, the method of making a transparent image bearing body for each of said drawings which comprises, providing a transparent body having a sensitized face, exposing the sensitized face of said body to one of said drawings, developing the exposed face to provide a variation in elevation between the photographically produced image line and the adjacent area of said face, and opaquing the image carrying face of the body within outlines of the image in varying tones to complete the cartoon images and utilizing the variation in elevation to confine the opaquing material within the outlines.

17. The method of producing animated cartoons from a series of cartoon drawings which comprises, providing a series of sensitized transparent sheets, photographically producing images of said series of drawings on a sensitized face of said series of transparent sheets in such a manner as to provide a variation in elevation between the image line and the adjacent surface of said face, opaquing the image carrying face of the sheets within outlines of the images in varying tones to complete the cartoon images and utilizing the variation in elevation to confine the opaquing material within the outlines, and photographing the series of completed images on successive frames of a sensitized film.

18. In the production of animated cartoons from a series of cartoon drawings, the method of making image bearing sheets which comprises, providing a series of sensitized transparent sheets,

exposing a sensitized face of said series of sensitized transparent sheets to said series of drawings, developing the exposed sheets to provide a variation in elevation between the photographically produced image line and the adjacent surface of the sheets, and opaquing the image carrying face of the sheets within outlines of the images in varying tones to complete the cartoon images and utilizing the variation in elevation to confine the opaquing material within the outlines.
